United States Patent Office.

JOHN SHARTLE, OF LIMA, INDIANA.

Letters Patent No. 72,549, dated December 24, 1867.

IMPROVEMENT IN GATES.

The Schedule referred to in these Letters Patent and making part of the same.

TO ALL WHOM IT MAY CONCERN:

Be it known that I, JOHN SHARTLE, of Lima, in the county of LaGrange, and State of Indiana, have invented a new and useful Improvement in Gates; and I do hereby declare that the following is a full, clear, and exact description thereof, which will enable those skilled in the art to make and use the same, reference being had to the accompanying drawings forming part of this specification.

This invention relates to an improvement in gates, and consists in so constructing and hanging the gate that it can be raised and lowered in position for overcoming obstacles, such as snow, mud, &c.

The accompanying drawing is a front view, partly in section, of my improved gate.

Similar letters of reference indicate corresponding parts.

A is the gate-post, B the gate, which in the present instance consists of the upper horizontal bars F and uprights C, D, and E. The uprights C, D, and E are extended above the top of the gate B, and in the upper end of upright C is pivoted one end of the bar F, which, passing through the extension of upright D, and the slotted extension of upright E, is by its other end hung by a pintle, b, to the upper end of gate-post A, the gate, by its lower portion, being hung to the said gate-post by the jaws or curved arms a, partially encircling the same. H is a cord, fastened at one end to the rail F' at h, from which it passes down and round the pulley g hung upon the gate, and thence up to a windlass-drum, I, also hung upon the gate, but at or near the top of said gate. K is a handle to windlass I, by means whereof the windlass can be turned for the purpose of winding the cord H, thus raising the gate, passing, by its slotted uprights D and E, over the bar or rail F', as is obvious without further explanation. M is a pawl, hung at one end to the gate B in suitable position for its other end to be engaged with the ratchet-teeth formed around the windlass-drum I, and thus to hold the said drum from turning back. When desired to lower the gate, the pawl M is raised from the said ratchet-teeth, leaving the windlass free to turn by the weight of the gate pulling on the cord. L is the bolt for fastening the gate when closed, which bolt sets into the vertical groove l made in the end post L'. This groove allows the bolt to play up and down in the post when the gate is raised or lowered, without it being necessary to withdraw said bolt.

I claim as new, and desire to secure by Letters Patent—

The bar or rail F', pivoted at one end to a gate, and at the other hung to a gate-post, A, in combination with the windlass-drum I, hung to the gate, and connected to said rail F' by the cord H, substantially as above set forth and described.

JOHN SHARTLE.
